UNITED STATES PATENT OFFICE.

OMAR A. CAVINS, OF LOS ANGELES, CALIFORNIA.

WELL TOOL.

Application filed January 17, 1923. Serial No. 613,126.

My invention is an improved well tool. In drilling deep wells, such as oil wells, by the cable tool method, the bottom of the bore fills with sand, and so forth, from time to time. The same often happens with completed wells. This sand, and so forth, must be removed, and at present this is usually done with tools known as bailers of which there are several types falling in general under the two heads of ordinary gravity filling and pump bailers. The sand in the bottom of the hole becomes very compact and difficult to remove, the present method being to agitate the material before its removal. My bailer derives its advantages over other types from the high pressure at which it operates when used under great heads of liquid in deep bore holes.

This high pressure enables it to take up, without immediate previous agitation, compacted sand and similar material which ordinary gravity filling bailers and those of the so-called pump type do not successfully handle.

In the drawing in which my invention is illustrated, I have shown the preferred form thereof but it may be embodied in other forms, and in the specification and appended claims I wish to cover my invention in whatever form it may be embodied.

Referring to the drawing:

Figure 1 is a sectional view of my well tool.

Figure 2 is a fragmentary sectional view of the upper end of my well tool.

Figure 3 is a plan view of the spider head clamp and rod guide.

Figure 4 is a fragmentary sectional view of the central section of my well tool.

Figure 5 is an enlarged sectional view of the control valve in open position.

Figure 6 is a view of the same in closed position.

Figure 7 is a sectional view of the equalization valve.

Figure 8 is a fragmentary sectional view of the lower section of my well tool.

Figure 9 is a sectional view of a modified form of lower section.

Figure 10 is a sectional view of a further modified form of lower section.

Referring more particularly to the drawing:

The bailer consists of the shell or tube 1 and its several parts; the bail spider 2 and its several parts; the vacuum-pressure tank

3 with its several parts; the discharge valve 4; the intake valve 5 and the equalization valve 6.

The shell or tube 1 consists of three tubes 60 7, 8 and 9 of equal diameter and thickness of material. These are joined to form one tube by the seating collar 10 joining the tubes 7 and 8 and by the discharge valve 4 which joins the tubes 8 and 9. 65

The spider 2 consists of a head 11, arms 12 and a lifting stem 13. The head 11 and arms 12 are made in one piece and the latter joined to the shell or tube 1 by rivets, welding or other suitable method. 70

The lifting stem 13 has an eye 14 formed thereon to receive the cable by which the bailer is supported and a shoulder 15 with convex upper surface to fit in the concave under surface of the head 11. The lifting 75 stem 13 is threaded at its lower end so that it can be coupled with the valve rod 16 by means of the coupling 17. The head 11 is slotted longitudinally as at 18 and between two of the arms 12. The lifting stem is inserted into the head through this slot which is then closed by the split ring 19. 80

The vacuum-pressure tank 3 consists of the outer shell 20 and a central tube 21 extending vertically therethrough. The valve 85 rod 16 is adapted to reciprocate within the tube 21. A seating ring 22 is formed on the upper end of the shell 20 by means of which the vacuum-pressure tank hangs in the shell 1 of the bailer. When the upper tube 7 of 90 the shell 1 is tightly screwed into the seating collar 10 the lower end of the tube seats on the flange 22 making a tight joint so that neither liquid nor gas can pass. The central tube 21 is welded or otherwise firmly joined 95 at its lower and upper ends to the vacuum-pressure tank shell 20. An elongated guide 23 properly formed and finished on the lower end of the tube 21 serves as a guide to make a tight fit with the properly finished 100 lower end of the valve rod 16 in which the valve rod 16 moves longitudinally.

The guide 23 has one or more horizontal holes 24 drilled through it into an annular port 25. On the shoulder 26 of the tube 21 105 rests the shoulder 27 of the valve rod when the rod is in its lower position. The hole 28 in the lower end of the tube 21 provides a means of flushing out the vacuum-pressure tank. With the safety valve 29 removed 110 and the valve rod entirely removed from the center tube 21 the vacuum-pressure tank

can be flushed out by introducing liquid at the hole from which the valve 29 was removed and allowing it to escape at hole 28.

When the rod 16 is in its lower position 5 (as shown in Fig. 5) the shoulder 27 rests on the shoulder 26 of the central tube 21. The lower end of the valve rod 16 is bored longitudinally as at 30 and a transverse bore 31 extends into the bore 30 at the top thereof. By means of this passage when the valve rod is in the lower position (as shown in Fig. 5) there is a passageway through which gas or liquid may pass from the shell into the tank 3. When the valve rod is in 10 its upper position this passage is closed (as shown in Fig. 6). A plug 32 has a small longitudinal hole formed therein and screws into the lower extremity of the valve rod 16. By using plugs with different sized holes, 15 different sized passages can be provided into the tank 3 but one of small bore is preferred so that the equalization of pressures will take place slowly.

The safety valve 29 is an ordinary spring 25 seating safety valve which can be adjusted so as to keep the excess of internal pressure over the external pressure in the vacuum-pressure tank 3 at any desired amount.

The discharge valve 4 consists of the in- 30 ternal coupling or nipple 40 and the external ring 41. The inside surface of the ring 41 and the outside surface of the coupling or nipple 40 are machined so that the ring will slide on the coupling or nipple and make a 35 tight joint therewith. The ring 41 has a plurality of holes 42 formed therein and the coupling 40 has holes 43 formed therein. By turning the ring 41 the holes 42 can be made to coincide with the holes 43 of the 40 coupling 40 and thus form passages from the interior to the exterior of the shell or tube 1 of the bailer, or they can be placed over blank spaces on the coupling 40 and thus close these passages.

45 The intake valve 5 is the common bailer bottom now in common use on ordinary bailers.

The equalization valve 6 is situated at a 50 suitable distance below the bottom of the vacuum-pressure tank 3. It consists of the elbow tube 45 threaded externally at one end so as to screw into the shell or tube 1 of the bailer and internally at both ends; at one 55 to receive the external plug 46 and at the other to receive the ball seat 47. The ball 48 seats on the ball seat 47. With the plug 46 removed this valve permits the escape of pressure inside the bailer in excess of that outside, but when the pressure on the outside exceeds that on the inside of the bailer 60 the valve prevents the equalization of these pressures.

The operation of my invention is as follows:

65 With the bailer assembled as described

and with the safety valve 29 set as desired, say for 100 pounds per square inch pressure, the discharge valve 4 closed and the plug 46 removed from the equalization valve 6, the bailer is lowered by cable into the bore hole 70 which must contain liquid for the successful operation of the bailer. The bailer must be of sufficient weight to sink through the liquid. The weight of the bailer is sustained by the shoulder 15 on the lifting rod 13. 75 The lifting of the valve rod 16 closes the port 31 in the bottom thereof. The bailer is lowered to the bottom of the hole through the liquid. When bottom is reached and the weight of the bailer rests upon the material 80 in the bottom of the hole, the lifting rod 13 and the valve rod 16 drop until the shoulder 27 rests upon the shoulder 26. This dropping of the valve rod 16 opens the port 31 in the bottom of the rod 16 and produces 85 in effect a vacuum in the bailer, for just before the bailer comes to rest on the bottom, the pressure inside the tank 3 is equal to atmospheric pressure, while that inside of the shell and outside the bailer is that of 90 the bottom of the well, the amount depending upon the column of liquid in the hole and the kind of liquid. Therefore, when the port 31 in the lower part of the rod 16 is opened, the sand, mud and other loose material upon which the bailer rests, moves up into the bailer due to the greater pressure on the outside of the bailer. The rate of flow of the material into the bailer depends mainly upon the size of the hole in the 100 plug 32.

When the pressure within and without the vacuum-pressure tank is equalized the flow of material into the bailer ceases. Then if the bailer is lifted the port 31 in the bottom 105 of the rod 16 and valve 5 close. The bailer is then lifted to the surface with its load, which is held in the bailer by the valve 5. As it is lifted the pressure in the vacuum-pressure tank escapes through the safety 110 valve 29 until, at the surface of the ground, only the pressure for which the valve is set remains; in this assumed case 100 pounds per square inch.

The pressure within the body of the bailer 115 which would otherwise be that of the bottom of the well, if the sand and like material in the bailer prevented its escape downward, is reduced to atmospheric pressure, when the bailer has reached the surface, by the escape 120 of the pressure outward through the equalization valve 6. When the bailer appears at the surface on being raised from the bottom of the bore hole the plug 46 is inserted and the ring 41 of the discharge valve 4 turned 125 until the holes in it coincide with those of the coupling 40. The bailer is then set down in the discharge trough of the drilling rig. This takes the weight from the lifting stem 130 which permits the valve rod 16 to drop,

opening the port 31 in the bottom of the vacuum-pressure tank and causing the pressure in the tank to force the material inside of the bailer out through the holes of the discharge valve 4. When the bailer has emptied itself the discharge valve 4 can be closed again, the plug 46 removed, the bailer lowered into the hole and the operation repeated.

10 The type of bottom shown in Figure 9 can be used instead of the last joint of the shell or tube 1 and the ordinary bottom 5 when it is desired to clean out around lost tools preparatory to fishing for them. This 15 consists of an elongated curved nose 50. With the special shoe 55 as shown in Figure 10 it can be used as a fishing tool to remove small objects such as under-reamer lugs from the hole.

20 When this special basket shoe is used it is substituted for the intake valve 5 and is attached to the bailer by an ordinary nipple which is substituted for the discharge valve 4. With this basket shoe in place the apparatus 25 is lowered into the bore hole. When the apparatus strikes bottom the bailer is pushed downward by the external pressure on the bailer which exceeds that within the bailer, after the vacuum-pressure tank valve 30 has opened. This causes the sand and other loose material, together with under-reamer lugs and other small objects, to enter the bailer tube pushing aside the flexible prongs 56. When the bailer is lifted out of the hole 35 the under-reamer lugs, and so forth, are retained within the bailer tube by the flexible prongs 56, or if they were unable to enter the tube of the bailer they may be held on the barbs of the flexible prongs 57.

40 Having described my invention, I claim:

1. A well tool adapted to be inserted in a well bore, comprising a tank, a shell surrounding said tank and extending below the same, said shell having an intake valve in the lower end thereof, means whereby the interior of said tank is placed in open communication with the shell when at the bottom of the well bore, said means being adapted to be closed as the tool is raised from the bottom of the well bore, said means being operable at the top of the well bore so as to cause the pressure in the tank to eject the contents of the shell.

2. A well tool adapted to be inserted in a well bore, comprising a shell, a valve at the bottom of said shell, through which material may enter said shell, a tank positioned in said shell and having a valve therein adapted to be opened after the tool has come to rest at the bottom of the well bore, the lower pressures in the tank as compared with that in the shell serving as a means to suck material through the valve in the bottom of said shell, automatic means to close the valve and the tank when the tool is

raised from the well bore, said valve in said tank being adapted to be opened at the top of the well bore so that the pressure in said tank will eject the material from said shell.

3. A well tool adapted to be inserted in a well bore comprising a shell, a valve at the bottom of said shell, through which material may enter said shell, means positioned in said shell adapted to alternately exert a suction effect on said material, and a pressure thereon to eject the same, a valve in said means through which fluid is adapted to pass slowly, and, means for controlling said valve from the surface of the ground.

4. A well tool adapted to be inserted in a well bore comprising a shell, a valve at the bottom of said shell through which material may enter said shell, means positioned in said shell adapted to alternately exert a suction effect on said material and a pressure thereon to eject the same, a valve in said means through which fluid is adapted to pass slowly, means for controlling said valve from the surface of the ground, an equalizing valve in the shell below said means, and a relief valve at the top of said means.

5. A well tool adapted to be inserted in a well bore comprising a shell, a valve at the bottom of said shell through which material enters said shell, a pressure tank positioned in said shell adapted to exert a pressure on said material to discharge the same, a valve in said tank through which fluid under pressure is adapted to pass, means for controlling said valve from above said shell, said shells having a plurality of holes above the valve through which the contents may be discharged.

6. A well tool adapted to be inserted in a well bore comprising a shell, a valve at the bottom of said shell through which material enters said shell, a pressure tank positioned in said shell, a tube extending through said tank, a rod adapted to reciprocate in said tube, said rod having a longitudinal bore therein communicating with the interior of said tank, and means for controlling said rod to open or close the communication with said tank.

7. A well tool adapted to be inserted in a well bore comprising a shell, a valve at the bottom of said shell through which material enters said shell, a tank positioned in said shell, a tube extending through said tank, a rod adapted to reciprocate in said tube, said rod having a longitudinal bore therein communicating with the interior of said tank, means for controlling said rod to open or close the communication with said tank, a lift rod slidably mounted in said shell, said first named rod being coupled to said lift rod whereby the first named rod is actuated.

In testimony whereof I affix my signature.
OMAR A. CAVINS.
